UNITED STATES PATENT OFFICE.

JOHN ALEXANDER GUINN, OF ANGUS, IOWA.

AUTOMATIC FIRE-EXTINGUISHER FOR RAILWAY-CAR STOVES.

SPECIFICATION forming part of Letters Patent No. 441,156, dated November 25, 1890.

Application filed August 8, 1887. Serial No. 246,457. (No model.)

To all whom it may concern:

Be it known that I, JOHN ALEXANDER GUINN, a citizen of the United States, residing at Angus, in the county of Boone and 5 State of Iowa, have invented certain new and useful Improvements in Automatic Fire-Extinguishers for Railway-Car Stoves; and I do hereby declare the following to be a full, clear, and exact description of the invention, such 10 as will enable others skilled in the art to which it appertains to make and use the same.

This invention relates to automatic fire-extinguishers for railway-car stoves.

The object is to produce a swift, sure, and 15 safe means of extinguishing the fire in railway-car stoves in case of an accident.

With these objects in view the invention consists in a reservoir or cylinder subdivided into two compartments, the lower one being 20 filled with water or some other suitable fluid for extinguishing fire, the upper one with compressed air, the two being separated by a floating piston-head, a pipe leading from the bottom of said reservoir to the fire-pot in 25 the stove, the said pipe having a valve placed between the reservoir and the stove.

The invention furthermore consists in a reservoir containing water or any other fluid suitable for extinguishing fire, a pipe leading 30 from the bottom of said reservoir to the fire-pot in the stove, the said pipe having a gate-valve placed upon it between the reservoir and stove, and a ball or weight designed to open said valve by falling, as in case of an accident, thus allowing the water or fluid from 35 the reservoir to flow in upon the fire and extinguish it, and, finally, in various other details of construction, as hereinafter fully set forth.

40 In the accompanying drawings, forming part of this specification, and in which like letters of reference indicate corresponding parts, Figure 1 is a side elevation of the invention, showing the cylinder or reservoir in position in the end of the car, with the upper part of said cylinder cut away to show the floating piston-head, the air-pressure gage attached to the side of the said cylinder near the top, the pipe leading from the reservoir 45 to the fire-pot in the stove, the valve attached to said pipe, and a lever or arm to operate

the valve and regulate the flow of water, together with a weight or ball, and a chain or rope designed to operate the said arm in case of an accident. Fig. 2 is a detail view of 55 the gate-valve. Fig. 3 is a perspective view of the floating piston-head on larger scale than Fig. 1.

In the drawings, A represents the cylinder attached to the side or in the corner of a car, 60 said cylinder being provided with two compartments, the upper compartment a being designed to contain compressed air and the lower one a² to contain water or other suitable fluid for extinguishing fire, the two compartments being separated by a floating piston-head a', consisting of a disk a⁵, made of suitable metal having sufficient rigidity for the purpose and provided with an upward-extending flange or rim a⁶ around its edge. 70 The upper compartment is also provided with an air-pressure gage A', placed on the side of said compartment near the top.

At or near the bottom of the lower compartment a² is a cock a⁴, the same being designed 75 as an inlet for the fluid when the chamber is to be filled.

In the center of the top or cap of the cylinder or on the side near the top is a cock a³ provided with a threaded nozzle designed to 80 engage the threaded collar of the hose or pipe of an air-pump or other suitable contrivance designed to compress air at a high pressure, so that in the process of charging the chamber said pipe will be held in position. 85

At the lower side of the water-chamber a² is a pipe B, connecting the said chamber with the fire-pot of the stove. The pipe B is provided with a gate-valve b, said valve being placed on the pipe between the cylinder and 90 stove and on or nearly on a level with the top of the body of fire in the stove in order to be easily within reach.

b' is the valve-spindle, threaded, as shown, at its end, and provided with a threaded thumb-nut b², having legs adapting it to be turned by the thumb and finger. 95

Pivoted on the bracket b³ which rises from the body of the valve-seat is a lever b⁴, one end of which embraces and is connected with the thumb-nut b², the object of the latter being to adjust the throw of the lever in relation to the 100

valve and the valve-seat, for it is evident that if the thumb-nut be screwed downward the valve will be raised more than if the nut were higher on the valve-spindle.

5 In the end of the lever b^4 is an opening b^5 , by which means the rope or chain may be attached to the lever. This rope or chain extends downward through a tube c , attached to the delivery-pipe in the top of the reservoir, 10 and is fastened to a weight D , seated in a cup-shaped disk E . The disk being lower in the center than at the edges will naturally secure the ball or weight in order to prevent its position being changed by the ordinary vibration 15 of the car while running; but when the running-gear changes its position to any great extent with reference to the car-body—as, for instance, when the running-gear leaves the track—such change of position in the running-gear will naturally throw the ball from 20 its position, and in falling will open the valve b , and thus allow the water or fluid to flow in upon the fire and extinguish it.

To make this invention operative the lower 25 compartment of the cylinder or reservoir a^2 is filled with water or other fluid suitable for extinguishing fire by means of the cock a^4 , and when filled the cock is closed, care being taken to introduce the water in such a manner 30 that the piston-head will remain on its surface and rise with it. The hose or pipe of an air-pump or other suitable contrivance designed to compress air at a high pressure is then attached to the nozzle of the cock a^3 in 35 the cap or top or on the side near the top of the cylinder a . The chamber is then charged with air until a pressure sufficient to insure the perfect working of the apparatus has been obtained. The cock a^3 is then closed. 40 It is to be distinctly understood that the air-pressure is not derived or in any way connected with the air-brakes. After the reservoirs have been so charged the apparatus is ready for operation. If from any cause 45 the running-gear should assume an abnormal position with reference to the car-body, the weight D will be thrown from its position in

the cup-shaped disk E , and in falling will open the valve b , and the compressed air in the chamber a , acting upon the floating piston-head a' , will force the fluid or water contained in the chamber a^2 through the pipe B to the fire-pot in the stove with great force, thus quickly extinguishing the fire. 50

The cylinder or reservoir should be made 55 of some material capable of withstanding the pressure requisite to the perfect working of the invention, preferably of copper or some alloy of the same, with its interior smoothly finished, in order that the floating piston-head 60 may move easily when the air-pressure is brought to bear upon said piston-head. The piston-head should be made of some non-corrosive metal, preferably copper, and surrounded on its periphery by a flange or rim much wider 65 than the thickness of the piston-head and fitted snugly in the cylinder to prevent its assuming an improper position with reference to the cylinder when the position of said cylinder is changed by an accident. 70

Having thus fully described my invention, what I claim as new, and desire to secure by Letters Patent, is—

An apparatus for extinguishing fire in railway-car stoves, comprising a reservoir 75 divided horizontally by a floating piston, the upper part having a valve or cock to cause it to hold air under pressure and the lower part adapted to contain liquid, a valved pipe leading from the liquid-chamber to the stove, a 80 valve-stem extending upward from said valve and having an adjustable stop, and a valve-operating mechanism comprising a lever pivoted on a bracket-arm and having a sliding connection with the valve-stem at one end 85 and carrying a chain at the other, a guide-tube for said chain, and a poised weight on the chain, substantially as described.

In testimony whereof I affix my signature in presence of two witnesses.

JOHN ALEXANDER GUINN.
